UNITED STATES PATENT OFFICE.

LAURENT RUEL, OF MERRIMAC, MASSACHUSETTS.

MACHINE FOR MAKING FELT BOOTS.

SPECIFICATION forming part of Letters Patent No. 308,282, dated November 18, 1884.

Application filed September 12, 1884. (No model.) Patented in Canada June 14, 1884, No. 19,559.

To all whom it may concern:

Be it known that I, LAURENT RUEL, a citizen of the United States, residing at Merrimac, in the county of Essex and State of Massachusetts, have invented certain new and useful Improvements in Machines for Making Felt Boots; and I do hereby declare the following to be a full, clear, and exact description of the same.

10 My invention is embodied in a machine for steaming and lasting or molding felt boots, and the construction and operation of which will be hereinafter fully described, reference being had to the accompanying drawings, in
15 which—

Figure 1 is a geometrical front elevation of a machine embodying my invention. Fig. 2 is a right side elevation; Fig. 3, a left side elevation. Fig. 4 is a plan view, and Fig. 5
20 is a sectional elevation of the treeing and lasting mechanism.

Like letters designate corresponding parts in all the figures.

In the drawings, A represents the frame of
25 the machine, provided with the top a.

B is a steaming-vat, in which the stocks or partly-formed boots are softened by steam before being stretched and molded into proper shape as finished boots, and to suit this purpose the vat is provided with two bottoms, b, between which steam is admitted, the upper bottom having numerous perforations through which the steam ascends to saturate the felt stocks in the body of the vat.

30 Attached to the frame A, and convenient to the vat B, is a device for stretching laterally the leg portions of the boots, consisting mainly of the jaws c c'. The jaw c is fixed rigidly upright, while the jaw c' is pivoted at its lower end to the frame. Its upper end is held against the upper end of the jaw c by the spring d, and is moved back from it, when desired, by the eccentric e being rotated by the lever f.

45 C is a hollow cylinder projecting up through the top a, and supported by the base D, which rests on the frame A. Into this cylinder, through a steam-tight packing at g in its lower end, a pipe, E, works similarly to a piston-rod. On that end of the pipe E which is with-

in the cylinder is fixed a piston-head, h, which slides up and down smoothly in the bored-out cylinder C. Standing upright on this piston-head, but not attached to it, are the two tree-pieces F F', which, when closed together, may 55 slide down inside the cylinder, but, when the piston-head carries them above the head of the cylinder, may be moved apart, as shown in Fig. 2, to the extent of the length of the arms i, which form a toggle-joint, by which 60 they are hinged to a rod, j, which passes down through a steam-tight packing in the lower end of the pipe E, and thence through a slit in the floor of the building or the machine. That part of the rod which passes through the 65 floor is made broad and flat, by which the rod is kept from turning.

When the tree-pieces are carried above the cylinder, the upper shoulders of this broad part of the rod will have raised the foot-lever 70 G, which, when depressed by the operator, draws down the rod j, and with it the arms of the toggle-joint i, thereby spreading apart the tree-pieces F F'. The piston-head and the tree-pieces are raised in the cylinder by means of a 75 rack, k, fixed on the pipe E, and into which a pinion, l, works. On the same shaft on which the pinion l is fixed are also attached the ratchet-wheel m, into which the pawl n engages to prevent backward motion, and the pulley H, 8c which is connected by the belt o with the driving-power. The belt o is put on sufficiently loose that it will not operate the machine, except pressed upon by the tightener I, which is held up by the spring p, except when depressed 85 by the operator bearing on the foot-lever q, which is connected with the tightener by the connecting-rod r, for the purpose of raising the tree-pieces out of the cylinder. When they have reached the proper height, the pressure 90 is taken off the lever q, when the spring p will immediately lift the tightener, and the piston and tree-pieces would at once descend into the cylinder; but they are prevented from doing so by the pawl n holding the ratchet m. In a 95 groove in the rear side of the tree-piece F' is dovetailed the heeler J, which may be moved freely up and down in said groove. When the tree-pieces are up and extended apart, the lower end of the heeler will be immediately over the 100

lifting-rod K, which is moved up and down in suitable guides on the outside of the cylinder C by the levers L and M, which are connected together and fulcrumed in any approved manner, and the latter of which projects from the front of the machine convenient to be operated by the foot of the workman. s is a steam-pipe leading from any convenient source of supply, and branching off into the steaming-vat in one direction and into the steam-cylinder in the other direction, for the purpose hereinafter specified. t t' are the valve-handles by which steam is turned on or off when required. N is a last, upon which the floor part of the boot is formed. It is placed on the upper end of the tree-piece F, the toe pointing upward, and may afterward be turned forward, so as to give the proper direction to the foot of the boot.

The operation of this machine may be described as follows: The felt stock to which this machine is intended to give the proper boot shape is simply a small sack, the toe end being closed. When this stock has been sufficiently softened by the steam in the vat B, it is drawn over the jaws c c', by which it may be stretched to any desired extent by turning the eccentric e, as above described. It is then removed, and the tree-pieces F F' and piston h being lowered in the cylinder C to their full extent, its open end is drawn over the head of the cylinder, on which it is firmly held by the clamps u u, which slide in suitable ways on the top a, and are pressed forward against the cylinder by the levered eccentrics v v and backward by the springs w w, which may be fixed in any manner to the table-top a. Steam is admitted to the cylinder, from which it also fills the stock on the tree-pieces, keeping them soft and moist. The power is then applied by bearing down the foot-lever q. The working of the pinion l in the rack k causes the tree-pieces to be shoved up into the felt stock until it is sufficiently stretched endwise. It will then be found that the shoulders of the broad part of the rod j have raised the foot-lever G, which, when depressed by the foot of the operator, draws down the toggle-joint formed by the arms i i, and thereby moves the tree-pieces F and F' apart, thereby stretching the felt stock laterally. The toe of the last, which has hitherto pointed upward, is now turned down forward. The heel portion of the boot receives its proper angular shape from the heeler J, which is moved upward into the

stock by pressing down the lever M. After 55 remaining a sufficient length of time in this position the foot-lever G is allowed to rise and the tree-pieces to close together. The clamps u are then withdrawn, and the finished boot may be removed from the machine. 60

What I claim as my invention, and desire to secure by Letters Patent, is—

1. In a felt-boot machine, the vat B, having the two bottoms b, the upper one being perforated, as and for the purpose set forth. 65

2. In a felt-boot machine, the jaws c c', spring d, eccentric e, and lever f, substantially as described.

3. The cylinder C, placed as shown, and the pipe E, working in said cylinder, carrying the 70 piston h and rack k, substantially as shown and described.

4. The tree-pieces F and F', connected by the arms i to the rod j in such a manner that the opposite arms, i, form a toggle-joint to be 75 operated upon by the rod j for moving the tree-pieces F F' together or apart, substantially as and for the purpose set forth.

5. In a felt-boot machine, the rod j, working 80 in the pipe E, and having its lower part widened where it passes through a slit in the floor of the machine or the building, so as thereby to prevent its turning, and operated upon by the foot-lever G, substantially as shown and described. 85

6. The arrangement and combination of the pulley H with the rack k, pinion b, ratchet-wheel m, and pawl n, substantially as and for the purpose set forth.

7. In a felt-boot machine, the combination 90 of the tree-piece F', having the heeler J sliding therein, with the lifting-rod K and the levers L and M, for operating the same, substantially as herein shown and described.

8. In a felt-boot machine, the combination 95 of the cylinder C with the clamps u, placed as shown, and movable by the levered eccentrics v, for the purpose herein specified.

9. In a felt-boot machine, the steam-pipe s, branching into the steaming-vat B, and the 100 cylinder C, substantially as and for the purpose herein specified.

Signed at Merrimac this 27th day of June, 1884.

LAURENT RUEL.
